WILLIAM W. GALBREATH, OF WARREN, OHIO

MACHINE FOR EXPANDING METAL

Application filed April 13, 1929. Serial No. 354,885.

This invention relates to improvements in machines for expanding metal and, more especially, metal lath of the slotted and ribbed type. For example, my machine may be used 5 for making expanded metal lath of the kind shown in the patent to L. E. Curtis, No. 1,655,091, granted January 3, 1928.

In that form of device embodying the features of my invention shown in the accompanying drawings—

Figure 1 is a view in side elevation; Fig. 2 is a top plan view; Fig. 3 is a view taken as indicated by the line 3 of Fig. 1; Fig. 4 is a view taken as indicated by the line 4 of Fig. 15 5; Fig. 5 is an end view; Fig. 6 is a sectional view of the rib-forming rollers; Fig. 7 is a view in perspective of one of the upper chain links; Fig. 8 is a similar view of one of the lower chain links; Fig. 9 is a vertical sectional view taken through a pair of chains; Fig. 10 is a bottom plan view of the upper chain; Fig. 11 is a top plan view of a piece of metal after being slotted and ribbed before 20 expanding; and Fig. 12 is a fragmentary view 25 of a portion of the metal between the ribs showing the same expanded.

As shown in the drawings, in Fig. 11 there is shown a piece of metal before being expanded by my improved machine. This 30 metal is provided with a plurality of downwardly projecting ribs or grooves, 10, 10. These ribs may project either downwardly or upwardly or some each way, but, merely for illustration, I have here shown these ribs 35 as all projecting downwardly.

The ribs may be formed by any suitable mechanism. The means for forming the ribs constitutes no part of the present invention. Merely for illustration, I have shown a pair 40 of rib-forming rollers 50 and 51 at the front of the machine. The upper roller 50 is provided with projecting annular flanges 52 operating in co-operating annular grooves 53 in the lower roller so that as the sheet of metal is passed between the rolls, five down-

wardly projecting ribs 10, 10 will be formed.

Either before or after forming the ribs, or contemporaneously therewith, the sheet of metal is subjected to a slitting or cutting operation for the formation of the slits 13 which, 50 in the metal illustrated, are in herringbone relation. The means for slitting the sheet forms no part of the present invention.

After being suitably slotted and ribbed, the metal is expanded by my improved expanding machine, which will now be described in detail.

As here shown, the expanding machine is adapted to receive the metal as it issues from the rollers 50 and 51 which form the ribs 10 60 therein. It is to be understood, however, that this arrangement is merely by way of illustration; and the metal might be fed to the expanding machine from the slitting mechanism or from any other feeding device. 65

The expanding machine comprises, in general, a suitable bed or support 14 carried by the legs 15. On the bed are arranged a plurality of diverging pairs of chains. Each pair of chains is adapted to grasp one of the 70 ribs 10, a strand of one chain lying above the metal and a strand of the other lying below. The chains are driven to carry the metal along through the machine and since the pairs of chains diverge as they move along, the 75 metal between the ribs is stretched or expanded into the condition shown in Fig. 12. It is to be understood, of course, that there should be provided one pair of chains for each rib 10. I have here shown five pairs of such 80 chains since, in this particular case, I am dealing with a piece of metal in which I have chosen to form five ribs.

Since each pair of chains is substantially the same, I need describe in detail but one. 85 I have indicated the lower chain, in general, by 16 and the upper chain by 17. The lower chain includes a series of links 16^a, as shown in Fig. 8, each having a groove 16^b in its upper surface adapted to receive one of the 90

- ribs 10. The upper chain includes a series of links, as shown in Fig. 7, indicated by 17^a, each having a downwardly projecting rib 17^b adapted to be pressed into the groove 5 16^b in the lower link so that the rib 10 of the metal will be securely grasped between the two chains. In each chain, the links 16^a and 17^a are connected by suitable connecting links 18. Each of the chains is endless. The 10 lower chain 16 passes over sprockets 19 and 20 at the front and rear ends, respectively, of the machine, and the upper chain likewise passes over sprockets 21 and 22.
- The sprockets 19 and 20 are mounted at the 15 ends of I-beams 23 and the sprockets 21 and 22 are mounted at the ends of beams 24 lying above the beams 23. The upper surface of each of the beams 23 is provided with a groove 25 accommodating a chain 16 and the 20 lower surface of this groove is provided with a suitable hardened metal liner or track member 26. The members 23 and 24 are held together at the ends by suitable tie bolts 28 and 29, respectively.
- 25 The chain 17, where it engages the metal, indicated, in general, by 30, lies in a groove 31 in the member 24; and above the chain is a series of long links 32, also lying in the groove, having on their under side hardened 30 metal strips 33 adapted to be pressed down against the chain 17 by means of springs 34. Numeral 35 indicates adjusting screws for varying the tension on the springs 34.
- The return strands of the upper chain 17 35 are brought back on top of the members 24 in grooves 36, having hardened metal liners 37. The return strands of the lower chains 16 are brought back in grooves 38 in the bed 14 under the members 23.
- 40 In the form shown, the sprockets 21 are all mounted on one shaft 39 and the sprockets 19 are mounted on a single shaft 40. The sprockets 22 are mounted on a shaft 41 and the sprockets 20, on a shaft 42. As thus 45 made, it will be seen that the chains (with the exception of the center pair) are not quite in alignment with the sprockets, but the angular diversions of the chains is so slight that they do not jump the sprockets.
- 50 The chains may be driven in any suitable manner, as, for example, by means of a sprocket 43 on the shaft 41, and the shafts 41 and 42 are preferably provided with meshing pinions 44 and 45 to drive the upper and 55 lower chains uniformly.
- Numerals 46, 46 indicate clamping bolts to pull the members 24 downwardly to cause the chains 16 and 17 to grip the metal 30 therebetween.
- 60 While I have shown and described certain 65 embodiments of my invention, it is to be understood that it is capable of many modifications. Changes, therefore, in the construction and arrangement may be made without departing from the spirit and scope of the

invention as disclosed in the appended claims, in which it is my intention to claim all novelty inherent in my invention as broadly as possible, in view of the prior art.

What I regard as new, and desire to secure by Letters Patent, is:

1. A machine for expanding slotted and ribbed metal including; a plurality of diverging pairs of chains, both chains of each pair moving parallel to each other and adapted to grasp the ribs of the metal therebetween; and means for driving said chains to cause the same to move forwardly and diverge from each other while carrying the metal therebetween. 75

2. A machine as claimed in claim 1, in which the chains are provided with co-operating parts adapted to engage the ribs of the metal. 80

3. A machine as claimed in claim 1, in which the chains are provided with links having co-operating ribs and grooves adapted to grip the ribs of the metal therebetween. 85

4. A machine for expanding ribbed and slotted metal including; a support; a plurality of longitudinally arranged diverging lower members mounted on said support; a plurality of longitudinally arranged diverging upper members mounted on said support above the lower members and parallel thereto; a pair of endless chains arranged in connection with each pair of said members, the chain on the upper member having a strand beneath the same and the chain on the lower member having a strand above the same, said strands lying close together and adapted to grip a rib of metal therebetween; means for pressing the upper and lower members toward each other to cause the strands of the chain to grip the ribs of metal between the same; and means for driving the chains to cause the same to move a piece of metal gripped between the same forwardly whereby the ribs will diverge with the chains and expand the metal therebetween. 95

5. Means for widening a metal blank having its cross section formed with displaced components comprising opposed sets of guides, each set including a plurality of laterally spaced channel members arranged in diverging relation, the members of one set being in opposed relation to similar members of the opposed set, a series of sprockets arranged at the beginning and end of each set of channel members, each series being laterally spaced to correspond with the spacing of the adjacent end of the channel members, an endless row of chain-like elements for each channel member, each row extending through the channel of their respective member and having driving engagement with the sprocket at each end of such member, the elements in a channel member of one set being in opposed relation to the elements in the corresponding channel 105

110

115

120

125

member of the opposed set, and means for driving each series of sprockets so as to move the elements of each row successively into and through the channel of their respective member and in a direction such that the spacing of corresponding points in the rows of each set is progressively increased as they move through the channels, the opposed elements being adapted to engage between them 5 determined portions of a blank which is fed between the sets and to move with such portions throughout the diverging movement so as to increase the mutual spacing of corresponding engaged portions of the blank 10 and thereby widen the same.

6. Means for widening a metal blank having its cross section formed with displaced components comprising laterally spaced rows of elements in which the elements of each 20 row are adapted to be fed into engagement with successive portions of the longitudinal margin of a displaced portion and to move a determined distance with the engaged portions during which movement the relative 25 spacing of corresponding points in each row is progressively increased so as to increase in like manner the relative spacing of the engaged portions of the blank and thereby widen the blank, and means for so moving 30 the elements.

7. Means for widening a metal blank having its cross section formed with displaced components comprising opposed sets of blank 35 engaging elements, each set being composed of at least two laterally spaced endless rows of elements, the rows of one set corresponding in arrangement to the rows of the other set and the elements of corresponding rows being adapted for movement along circuitous 40 paths which bring such elements successively into opposed relation for a determined distance of travel during which travel they cooperate to engage a determined portion of the blank between them and to maintain 45 their engagement with such portion, their movement being in a direction such as to increase progressively to a determined extent the mutual spacing of the rows of both sets whereby the mutual spacing of correspond- 50 ing engaged portions of the blank is increased in like manner and the blank thereby widened, and means for so moving the elements.

8. Means for widening a metal blank having its cross section formed with displaced 55 components comprising a plurality of laterally spaced chain-like rows of elements in which the elements of each row are respectively adapted for movement over a fixed circuitous path during a determined portion of 60 which the mutual spacing between corresponding elements of the various rows increases, the corresponding elements being adapted to engage corresponding portions of a blank as they approach the point at which 65 their mutual spacing begins to increase and

to maintain their respective engagement with their respective portion while their spacing increases whereby the mutual spacing of the corresponding engaged portions of the blank is increased in like manner and the blank 70 widened, and means for driving said elements.

9. Means for widening a metal blank having its cross section formed with displaced components comprising a plurality of laterally spaced chain-like rows of elements in which the elements of each row are respectively adapted for movement over a fixed circuitous path during a determined portion of which the mutual spacing between 80 corresponding elements of the various rows increases, the corresponding elements being adapted to engage corresponding portions of a blank as they approach the point at which their mutual spacing begins to increase and to maintain their respective engagement with their respective portion while their spacing increases whereby the mutual spacing of the corresponding engaged portions of the blank is increased in like manner and the blank 85 widened, a series of sprockets arranged to guide the elements of each row into engagement with the blank at the beginning of the widening operation, another series of sprockets arranged to guide the elements out of 90 engagement with the blank after the blank has been widened, and means for driving the elements.

10. Means for widening a metal blank having its cross section formed with displaced components comprising opposed sets of blank 100 engaging elements, each set including a plurality of laterally spaced endless rows of elements in which each row is adapted for movement over a fixed path, a portion of which is in diverging relation with corresponding portions of the paths of the other rows in the same set, the elements of one set being in opposed relation with corresponding elements of the opposed set during the 105 diverging movement, and means for driving the elements, the opposed elements being adapted to engage between them determined portions of a blank which is fed between the sets and to move with such portions throughout the diverging movement so as to increase 110 the mutual spacing of corresponding engaged portions of the blank and thereby widen the same.

11. Means for widening a metal blank having its cross section formed with displaced components comprising opposed sets of blank 120 engaging elements, each set including a plurality of laterally spaced endless chain-like rows of elements in which each row is adapted for movement over a fixed path, a portion of which is in diverging relation with corresponding portions of the paths of the other rows in the same set, the elements of one set being in opposed relation with correspond- 125

65 70 75 80 85 90 95 100 105 110 115 120 125 130

ing elements of the opposed set during the diverging movement, a pair of shafts respectively arranged in each set at the beginning and at the end of the diverging area, said shafts having driving engagement with the elements, and means for driving the shafts, the opposed elements being adapted to engage between them determined portions of a blank which is fed between the sets and to move with such portions throughout the diverging movement so as to increase the mutual spacing of corresponding engaged portions of the blank and thereby widen the same.

15 In witness whereof, I have hereunto set my hand this 10th day of April, 1929.

WILLIAM W. GALBREATH.
